[57] ABSTRACT

A method and apparatus for testing a plurality of space-divided equipment units, such as junctors, of a communication switching system having a switching network for establishing connections between calling and called lines in response to common equipment including a scanner for monitoring supervisory devices of the space-divided units for supervisory purposes, such as ticketing calls through the network, includes establishing a test connection through the network between a test circuit and a supervisory device under test, causing the test circuit to control the operation of the device under test, causing the scanner to sense the operation of the device under test, and determining whether the device under test is able to operate properly in response to the scanner.

METHOD AND APPARATUS FOR TESTING COMMUNICATIONS SWITCHING SYSTEM SPACE DIVIDED EQUIPMENT SUPERVISORY DEVICES

BACKGROUND OF THE INVENTION

1. Field of the Invention

The present invention relates to a method and apparatus for in-circuit testing of communication switching system supervisory devices which generate supervisory signals, such as ticketing signals, for processing by system common equipment.

2. Description of the Prior Art

Communication switching systems, such as electronic telephone systems, have employed switching networks for establishing selectively connections between calling and called lines in response to common equipment. Such systems also include a plurality of space-divided equipment units communicating with the common equipment for performing control operations in establishing the connections. One example of a control operation is the provision of supervisory signals, such as ticketing information signals, for billing purposes or for peg counting the number of calls. The common equipment includes a scanner for monitoring supervisory devices of the space-divided units generating the supervisory signals. It would be highly desirable to have a method and apparatus for testing the supervisory devices of the space-divided units to determine whether or not they are operating satisfactorily, since such devices provide critical information, such as billing information which must be accurate at all times or else the subscribers to the system may be billed incorrectly. Moreover, the tests of the devices should be performed in circuit, that is, with the device under test connected in the system and tested by other call processing circuits, since it would not be desirable to provide additional sensing circuits for each device due to the additional expense and the added risk of having the sensing circuits malfunction.

SUMMARY OF THE INVENTION

Therefore, it is the principal object of the present invention to provide a new and improved method and apparatus for testing communication switching system space-divided unit supervisory devices in an in-circuit manner and in an efficient and economical manner.

CROSS-REFERENCES TO RELATED APPLICATIONS

The preferred embodiment of the invention is incorporated in a COMMUNICATION SWITCHING SYSTEM WITH MARKER, REGISTER, AND OTHER SUBSYSTEMS COORDINATED BY A STORED PROGRAM CENTRAL PROCESSOR, U.S. Pat. application Ser. No. 130,133 filed Apr. 1, 1971 by K. E. Prescher, R. E. Schauer and F. B. Sikorski now abandoned, and a continuation-in-part thereof Ser. No. 342,323 filed Mar. 19, 1973 issued on Sept. 10, 1974, as U.S. Pat. No. 3,835,260, hereinafter referred to as the SYSTEM application. The system may also be referred to as No. 1 EAX or simply EAX.

The memory access, and the priority and interrupt circuits for the register-sender subsystem are covered by U.S. Pat. application Ser. No. 139,480 filed May 3, 1971 now U.S. Pat. No. 3,729,715, issued Apr. 24, 1973 by C. K. Buedel for a MEMORY ACCESS APPARATUS PROVIDING CYCLIC SEQUENTIAL

ACCESS BY A REGISTER SUBSYSTEM AND RANDOM ACCESS BY A MAIN PROCESSOR IN A COMMUNICATION SWITCHING SYSTEM, hereinafter referred to as the REGISTER-SENDER MEMORY

CONTROL patent application. The register-sender subsystem is described in U. S. Pat. application Ser. No. 201,851 filed Nov. 24, 1971 now U.S. Pat. No. 3,737,873 issued June 5, 1973 by S. E. Puccini for DATA PROCESSOR WITH CYCLIC SEQUENTIAL ACCESS TO MULTIPLEXED LOGIC AND MEMORY, hereinafter referred to as the REGISTER-SENDER patent application. Maintenance hardware features of the register-sender are described in four U.S. Pat. applications having the same disclosure filed 15 July 12, 1972, Ser. No. 270,909 now U.S. Pat. No. 3,784,801, issued Jan. 8, 1974 by J. P. Caputo and F. A. Weber for a DATA HANDLING SYSTEM ERROR AND FAULT DETECTING AND DISCRIMINATING MAINTENANCE ARRANGEMENT, Ser. No. 20 270,910, now U.S. Pat. No. 3,783,255, issued Jan. 1, 1974 by C. K. Buedel and J. P. Caputo for a DATA HANDLING SYSTEM MAINTENANCE ARRANGEMENT FOR PROCESSING SYSTEM TROUBLE CONDITIONS, Ser. No. 270,912 now U.S. Pat. No. 25 3,805,038 issued Apr. 16, 1974 by C. K. Buedel and J. P. Caputo for a DATA HANDLING SYSTEM MAINTENANCE ARRANGEMENT FOR PROCESSING SYSTEM FAULT CONDITIONS, and Ser. No. 270,916 now U.S. Pat. No. 3,783,256, issued Jan. 1, 1974 by J. P. Caputo and G. O'Toole for a DATA HANDLING SYSTEM MAINTENANCE ARRANGEMENT FOR CHECKING SIGNALS, these four applications being referred to hereinafter as the REGISTER-SENDER MAINTENANCE patent applications.

35 The marker for the system is disclosed in the U.S. Pat. No. 3,681,537, issued Aug. 1, 1972 by J. W. Eddy, H. G. Fitch, W. F. Mui and A. M. Valente for a MARKER FOR COMMUNICATION SWITCHING SYSTEM, and U.S. Pat. No. 3,678,208, issued July 18, 40 1972 by J. W. Eddy for a MARKER PATH FINDING ARRANGEMENT INCLUDING IMMEDIATE RING; and also in U.S. Pat. applications Ser. No. 281,586 filed Aug. 17, 1972 by J. W. Eddy for an INTERLOCK ARRANGEMENT FOR A COMMUNICATION 45 SWITCHING SYSTEM now U.S. Pat. No. 3,806,659, issued Apr. 23, 1974, Ser. No. 311,606 filed Dec. 4, 1972 by J. W. Eddy and S. E. Puccini for a COMMUNICATION SYSTEM CONTROL TRANSFER ARRANGEMENT now U.S. Pat. No. 3,830,983, issued 50 Aug. 20, 1974, Ser. No. 303,157 filed Nov. 2, 1972 by J. W. Eddy and S. E. Puccini for a COMMUNICATION SWITCHING SYSTEM INTERLOCK ARRANGEMENT now U.S. Pat. No. 3,809,822, issued 55 May 7, 1974, hereinafter referred to as the MARKER patents and applications.

The communication register and the marker transceivers are described in U.S. Pat. application Ser. No. 320,412 filed Jan. 2, 1973 by J. J. Vrba and C. K. Buedel for a COMMUNICATION SWITCHING SYSTEM TRANSCEIVER ARRANGEMENT FOR SERIAL TRANSMISSION now U.S. Pat. No. 3,814,859, issued June 4, 1974, hereinafter referred to as the COMMUNICATION REGISTER patent application.

60 65 The executive program for the data processor unit is disclosed in U.S. Pat. application Ser. No. 347,281 filed Apr. 2, 1973 by C. A. Kalat, E. F. Wodka, A. W. Clay and P. R. Harrington for a STORED PROGRAM CON

TROL IN A COMMUNICATION SWITCHING SYSTEM, hereinafter referred to as the EXECUTIVE PROGRAM patent application.

The computer third party circuit is disclosed in U.S. Pat. application Ser. No. 348,575, filed Apr. 6, 1973 for a DATA PROCESSOR SYSTEM DIAGNOSTIC ARRANGEMENT by L. V. Jones, et al., hereinafter referred to as the THIRD PARTY patent application. The data processor system localization program is disclosed in U.S. Pat. application Ser. No. 348,541, filed Apr. 6, 1973 for a "METHOD OF LOCALIZING THE CAUSES OF MALFUNCTIONS OCCURRING IN A DATA PROCESSOR SYSTEM by P. J. Keehn, R. C. Wegner, D. C. Robbins, D. Chang, W. K. Yuan and J. L. Clements, hereinafter referred to as the COMPUTER LOCALIZATION PROGRAM patent application.

The automatic test system for the system is disclosed in the following United States patent applications: H. R. Miller, L. J. Putchinski, and K. W. Vanderlei application Ser. No. 446,437, filed Feb. 27, 1974 H. R. Miller, L. J. Putchinski, K. W. Vanderlei and D. A. Heck application Ser. No. 446,433, filed Feb. 27, 1974; T. W. Crosley, H. R. Miller and L. J. Putchinski application Ser. No. 446,574, filed Feb. 27, 1974; L. J. Putchinski, H. R. Miller and K. W. Vanderlei application Ser. No. 446,576, filed Feb. 27, 1974; and H. R. Miller and T. W. Crosley application Ser. No. 446,575, filed Feb. 27, 1974.

The above system, register-sender, marker communication register, executive program, third party, computer localization program and automatic test system patents and applications are incorporated herein and made a part hereof as though fully set forth.

DESCRIPTION OF THE DRAWINGS

FIG. 1 is a simplified symbolic and functional block diagram of a communication switching system incorporating the principles of the present invention;

FIG. 2 is a block diagram flow chart of the method of the present invention; and

FIGS. 3-12 are flow chart diagrams of a software program for controlling the method and apparatus of the present invention.

DESCRIPTION OF THE PREFERRED EMBODIMENT

Referring now to FIG. 1, there is shown a data processing unit 10 which serves as the central coordinating unit and communication hub in a communication switching system, only a portion of which is shown in FIG. 1. The system of FIG. 1 is more fully described in the above-cited patents. A central processor 11 is the central control unit of the computer for obtaining program instructions stored in a main memory 12, interpret each instruction, and perform the necessary operations specified by the instruction. The CMM memory 12 stores the system control program, referred to as the system executive program as well as those application programs whose frequency of usage requires that they be locally available. A drum memory 13 provides mass storage for translation data, diagnostic programs, tables and other such information. An input/output device buffer provides the central processor with serial and/or parallel information concerning its associated teletype-writer device 14.

A register/sender unit 20 is a time-shared common control unit with the ability to register and process a large number of calls simultaneously from local lines or incoming trunks. A register/sender core memory RCM 21 stores digits to be received and send, and supervisory information pertaining to the call. A common logic 22 contains the control logic for call processing by the register/sender. A register junctor multiplex RJM 23 provides an interface between the space-divided register junctors 24 and the time-shared common logic 22. This multiplex converts time-shared signals to space-divided signals for controlling the register junctors and the register/sender RJM multiplexer space-divided signals for return to the common logic. 5 The local register junctor 24, which is one of a maximum 192 register junctors, the others not being shown, is the entry and exit point in the register/sender for information signalled through the switching network. It provides a facility for dial pulse sending and receiving, 10 dial tone, other signalling previously disclosed, and interface between the common logic and switching network and markers. Signals from lines and network circuits are received by the register junctor and forwarded to the common logic for processing. 15 A ticketing scanner unit 30 is a data gathering and reporting system used for customer billing, toll separation, traffic engineering studies, planning and evaluation of toll services and maintenance of toll facilities. A ticketing device buffer 31 provides the input/output 20 interface for the ticketing scanner unit to the data processor unit 10 for serving one of four peripheral adapters at a time. All interrupts and all data and instructions are routed through the buffer TDB, there being only one error interrupt and one ready interrupt associated 25 with the TDB buffer 31. The TDB data channel comprises 24 bits plus a parity bit, the parity bit being checked or generated according to the direction of transmission. The TDB buffer is equipped in duplicate, each unit serving one of a duplicate scanner unit and one of a duplicated pair of magnetic tape units. In normal operation, one TDB buffer is used to service the input/output operation to one scanner unit and the other TDB buffer services the duplicate magnetic tape unit. This arrangement is switched on alternate days. 30 The ticketing device buffer provides intermediate reception and storage of instruction and data information from the central processor to a peripheral adapter. The TDB buffer also provides checking facilities in the form of a parity check on a computer word and a 1 of N check on computer directives. A scanner peripheral adapter 33 receives data in a one computer word grouping of 24 bits from the central processor. The peripheral adapter interprets instructions received from the central processor via the TDB buffer into bytes for enabling one of fifteen battery drivers and one of sixteen ground switches in a current sensing circuit 34, which also includes 24 voltage monitors for retrieving groups of 24 contacts via toroidal core sense rings in a 35 monitored contacts matrix 35. The matrix includes a three dimensional scanning matrix for interrogating contacts associated with supervisory circuits, such as originating junctors, incoming trunks and outgoing trunks. The monitored contacts matrix provides isolation between the electronic scanner SPA and the electromechanical, high voltage and noise logic circuits of a slave relay circuit 45, which provides contact isolation from the ticketed originating junctor circuits, such 40 45 50 55 60 65

as the coin originating junctor 43, required for scanning purposes, all of the other types and kinds of originating junctors not being shown in the drawings. Complete flexibility is available via a distribution grouping of terminals such that any supervisory circuit can be scanned, up to a maximum of 5,760 scan points. Each junctor OJ or incoming trunk requires one scan point, while each outgoing trunk requires two scan points.

A switching network-markers unit 40 provides access into the communication switching system with high speed control to connect any call through the system to the desired destination. A terminating markers 41 of the network-marker units 40 include electronic logic circuits which control the selection of idle paths and the establishment of connections through the matrices, such as the selector matrix 44, of the network-markers unit 41. A line matrix R-stage 42 provides a concentrating matrix that allows the originating junctors to access lesser local register junctors LRJ. The coin originating junctor 43 is used for a call initiated from a regular line and for every call originated from a local paystation line (not shown), and remains in the connection for the duration of the call. The coin originating junctor extends signalling path of the calling line to the register junctor 24 in the register/sender unit 20, and at the same time provides a separate signalling path from the register junctor to the selector matrix 44. The coin originating junctor maintains the calling line, either a paystation or a regular line, isolated until cut-through is effected, at which time the calling party is switched through to the selector matrix inlet. The selector matrix 44 provides for intermediate mixing and distribution of the traffic from various trunks and junctors on its inlets to various trunks and junctors on its outlets. This three-stage network interconnects originating junctors and other equipment with special local facilities to a selector test outlet STO circuit 46 for access into the automatic test system 50.

Associated with the data processor, but as a separate equipment group, is the automatic test system 50, which serves as a centralized facility for interfacing between the maintenance personnel referred to as the "office craftsman" and the communication switching system and is the focal point for initiating test call routines and test programs, providing print-out of maintenance information, and provides special test equipment that are used in automatic testing in the exchange area. This equipment is used to test the trunks residing in the local office and testing of customer's lines served by an office located beyond the supervisory limits of the local test trunks in the main office. The maintenance routine logic unit 51 contains the electronic circuitry to provide sequence routine control for automatic testing of a communication switching system. The interface unit ITU 52 provides the necessary buffer logic from gates 54 and 55 between the electronic circuitry of the maintenance routine logic 51 and the electro-mechanical circuitry of the maintenance test unit MTU 53, which provides various circuits needed to generate and receive signals as indicated by relay coil K8, for routine testing of the space-divided equipment, and also to simulate other conditions necessary to complete the tests. The maintenance test connect circuit MTL 56 is an electromechanical single-stage switching network, which concentrates all of the test inlets and outlets of the network used for automatic testing into four unique

circuits, one of which is described herein, namely the selector test outlet 46.

Referring now to FIG. 1, peripheral adapter register circuit 39 controls twenty-four data bits to be read by the computer central processor via the ticketing device buffer from the current sensing circuit 34, which includes 24 voltage monitor circuits 38, and sixteen ground switches 36 and fifteen battery drivers 37 to enable the monitored contacts matrix toroidal core 10 which monitors a large group of contacts from a slave relay circuit 45, which in turn are each operated from a coin originating junctor via contact K4-A from relay K4, which is energized from ST lead 47 from the automatic test system interface unit.

15 Briefly, in operation, the scanner peripheral adapter instruction decode circuit 32, which controls the retrieving of data from the monitored contacts matrix, is supplied with sufficient address information from the system central processor on leads 101 through 104 and leads 105 through 108 to enable one of fifteen battery drivers 37 on leads 140 through 154 and enable one of sixteen ground switches 36 on leads 160 through 174 which in turn enables a current to flow through one of many contacts, such as contacts K10-A through K10C.

20 25 A. A set of relays K10-K100 controlling the respective contacts K10-A through K100-A are enabled by the coin originating junctor 43, which is one of a maximum of 2,880 coin originating junctors, the other ones of which not being shown in the drawings. The junctor 4 includes, among other components (not shown), two relays, K4 and K6, but it is to be understood that other relays (not shown) are required to perform the normal coin OJ operation. The coin OJ relay coils K4 and K6 are operated to check either the normal ticketing function or the paystation control function respectively, which operation results in the closure of relay contact K4-A, which in turn is monitored by causing the operation slave relay K10 of the slave relays K10 through K100. The monitored contacts matrix toroidal core whose outputs are sensed by one of twenty-four voltage monitor gates 38, enable leads 180 through 203 to the 24 bit register circuit 39 in the scanner peripheral adapter, which in turn supplies a full computer word of 24 bits on leads 110 through 133 to be read by the computer central processor 11 via the ticketing device buffer 31.

30 35 Referring now to the arrangement of the present invention in greater detail, the scanner peripheral adapter register circuit 39 has twenty-four output leads 110 through 133 connected to the ticketing device buffer for sending a full computer word of data to the central processor and the input leads 180 through 203 to the register are connected to the outputs of 24 voltage monitor circuits 38. The voltage monitor circuits 38 have its input leads 260 through 283 connected to a large group of toroidal cores in the monitored contacts matrix 35. A battery driver device 37 supplies the contacts of the slave relays via leads 220 through 233 and a ground switch device 36 via leads 160 through 175, allows the current to flow through the contacts and a diode in series with each contact for isolating from other current sources, and finally through the toroidal core sensing elements. The cores operate as current transformers, with many single turn input windings and an output winding, which is used by the voltage monitor devices 38. The matrix 35 reflects at every instant the status of the contacts that must be monitored.

for billing purposes. The battery driver 37 has 15 output leads 220 through 234 connected to the matrix, and has its 15 input leads 140 through 154 connected to the output instruction decode circuit 32, which in turn has its four inputs connected to the ticketing device buffer via leads 101 through 104. The ground switch circuit 36 has 16 output leads 240 through 255 connected to the matrix, and has 16 input leads 160 through 175 connected to the output of the instruction decode circuit, which in turn has its four inputs connected to the TDB 31 via leads 105 through 108. The voltage monitor device and main battery test gates designated MBT shown in the drawings are circuits, which when ground is applied to its input or its input is open circuited, supplies a true signal at its output, but when a negative battery potential is supplied thereto, a false indication is generated at its output. The ground switch device and the main ground switch relay driver illustrated in the drawings and designated ground switch and MGS respectively are electronic switches to provide a sink for a negative battery potential, which is sometimes supplied by a relay, and they may comprise two transistors (not shown) connected so that when a true signal is supplied at the input, a positive ground potential from the device is connected via the emitter-collector path of the output state in saturation to the negative battery source. The battery driver device shown in the drawing are electronic switches which are similar to the ground switch devices except that the battery devices switch negative battery potential as a source instead of a ground potential.

The slave relays K10 through K100 are a large group of relays which function to repeat the answer and hold operation of the coin originating junctors from the closure of the make contact of relay K4 for supplying a ground signal to the slave relays. The relay K4 is energized by ST lead 47, in normal operation from a terminating junctor upon detecting an answer supervision condition through the switching network, or from the automatic test system interface unit 52 via ground potential (not shown) supplied by MGS gate 54 for testing purposes. The relay K4, when operated, releases the ground potential through its normally closed contacts of its transfer contacts, but the ground potential remains on coil K4 via a path including the ST lead through the normally-closed contacts of the K6 relay transfer contacts and the normally-open contacts of the K4 relay transfer contacts. The relay coil K6 is energized for paystation type originations into the switching network from the C3 lead 212, which is energized by the output lead 211 of the MGS gate 25 via the line matrix R-stage 42 circuit. The MGS input lead 210 is enabled by the register sender common logic unit 22 through the register junctor multiplex 23. When relay K6 is energized, its normally-closed contacts release the ground potential from lead ST to relay K4 and supplies a holding ground potential to relay K4 via its normally-open contacts of its transfer contacts through the normally-open contacts of the operated transfer contacts of the relay K4 for supplying a ground holding potential for the relay K4.

Considering now a typical operation, assuming that the system has established a switching network test path to the coin originating junctor 43 and the other checks of the originating junctor operation have already been verified, after the proper system software operations have been performed for the terminating

process through the network, the terminating marker 41 is instructed to set up a path from the selector matrix inlet associated with the coin originating junctor to the selector matrix outlet associated with the STO circuit, which has access to the automatic test system 50. After the path is pulled, the register/sender unit 20 is instructed by the system software via register sender core memory word storage area 2A of the register junctor time slot associated with the selected register junctor 24 to cut the coin originating junctor through to the STO circuit. The register sender common logic unit 22 enables MGS gate 25 in the LRJ circuit 24, which supplies a ground potential to energize the coin OJ relay coil K6, which closes its normally-open contacts and opens its normally-closed contacts of its transfer pair. The automatic test system 50 is then instructed from the system software via words A through F of the maintenance routine adapter input register to supply a holding potential to the relay K4 via lead ST. The MRL unit 51 receives this instruction and enables MGS gate 54 in the interface unit 52, which switches the ground potential through relay K8 in the MTU circuit 53 and onto the ST lead via the selector test outlet 46 and the selector matrix 44. Relay coil K4 operates and disconnects the ground potential from the ST lead by opening the normally-closed K4 contacts. The ST lead ground potential is also blocked by the normally-closed K6 contacts already being opened by the register/sender. But, relay K4 remains operated from the closure of the normally-opened K4 contacts, which switches the ground potential that was already forwarded by the closure of the normally-opened K6 contact. Thus, relay K4 remains energized and its normally-opened contacts close to switch a ground potential to the slave relay K10. The system software then instructs the ticketing scanner unit 30 to monitor the status of slave relay K10 through the normally-opened contact K10-A of the relay K10. The scanner peripheral adapter instruction decode circuit 32 receives the X and Y instructions, which selects and enables the fifteenth battery driver lead 234 to switch a negative battery potential to the slave relay K10-A contacts, and the sixteenth ground switch lead 255 to provide a positive potential sink for the relay contacts K10-A to the negative source. A check is performed to insure that only one output signal of each one of the battery and ground devices has been activated. This check is necessary, since if more than one ground switch lead, for example, is switched on simultaneously, the current would flow between two groups of contacts and erroneous data would be returned. Current flows through the toroidal core only if the monitored contact K10-A is closed and its series isolation diode D1 is not open-circuited. The transformer type output lead 283 of the toroidal core supplies a true signal, which is sampled and the results of that scan, on a group of 24 contacts, are stored in the scanner peripheral adapter register 39 for transmission to the system program. A ready interrupt is generated and the system program collects the data to analyze its contents for closure of the monitored contacts. At the end of the scan cycle, the scanner clears itself in preparation for another cycle request. If the data indicates that a true signal was not true on lead 283, a trouble condition is output on the teletypewriter 14 indicating that this operation was not successful and either the coin originating junctor 43, slave relay K10, or monitored contacts matrix compo-

nents did not operate properly. If no trouble condition was detected, the coin originating junctor is released by the system software instructing the MRL unit 51 to turn off MGS switch 54 and remove the ground potential from the ST lead 47, which should cause relay K4 to remain operated through the K4 relay contacts and the relay K6 contacts, as previously described, to ground potential. Several other relays (not shown herein) also operate to collect the coins from the paystation before the coin originating junctor is finally released from the call. The ticketing scanner unit 30 is again instructed by the system software to monitor the slave relay K10 operation and return its status to the computer central processor. Relay K4 should have remained operated and K4 relay make contacts should have closed to switch a ground potential to close relay K10. The release of the MGS unit 54 is verified by monitoring the release of MTU relay coil K8 through normally-opened contact K8-A from MBT gate 55 turning off and providing a false signal on its output lead 214 to the MRL unit 51. This status is checked by the system software, and if found to be false a trouble message is output. If the ST bad ground was released, then the status of the slave relay is checked. If the relay K10 has released, a trouble message is output indicating that the coin originating junctor has a faulty relay contact in the path from the relay K4 through its normally-opened contacts and relay K6 normally-open contacts to ground. Considering all checks to be verified in the coin originating junctor operation with a paystation type of line, the normal subscriber type of line operation remains to be verified with the coin originating junctor.

The register/sender unit 20 is instructed to release relay K6 by turning off MGS unit 25 in the register junctor 24, which removes a ground potential from lead 211. The coin originating junctor should now completely release from the call and become available for normal call processing. The system software then instructs the ticketing scanner unit 30 to monitor the operation of the slave relay K10 again and report the results to the central processor. The relay K4 normally-open contacts should return to this normal state, thus releasing slave relay K10, which opens its relay contacts K10-A. This status is monitored by the ticketing scanner unit and analyzed by the originating junctor routine module. If the data indicates that relay contacts K4-A have not opened, a trouble message is output to indicate that either the coin originating junctor 43, slave relay K10, or the monitored contacts matrix is at fault. When the relay K4 has been verified to have released, the system re-establishes a switching network path to the coin originating junctor 43 and the proper system translations have been performed for the terminating process through the network and the terminating marker establishes a selector matrix path to the STO circuit 46. The system software then instructs MRL unit 51 of the automatic test system to turn on MGS unit 54 to switch a ground potential on ST lead 47 to operate coin OJ relay K4. The relay K4 operates and causes its normally-closed contacts to open to attempt to release the ground to relay K4, but the path through the relay K6 normally-closed contacts and the relay K4 normally-opened contacts, which have closed, re-establishes the ground potential to relay K4. The status of slave relay K10 is monitored again as previously described and the results analyzed by system software.

Any failure condition is output and finally the automatic test system is instructed to release the ST lead 47 ground potential, which drops relay K4 and subsequently the coin originating junctor.

Software Program Procedures

The automatic test system originating junctor test routining module OJ TEST-V57 provides routining, localization and repair verification of the three types of originating junctors OJ, regular, metering and coin, that can exist in a communication switching system. This disclosure is only concerned with the coin OJ operation and testing in the switching system. The disclosed method of testing the ticketing contacts of the coin OJ involves testing the junctor completely twice, once as a coin OJ application and once as a regular OJ in operation. This insures the full operational characteristics of the coin OJ have been verified due to the possible intermixing of paystation and non-paystation lines in the same line A-B group, which does not allow for the originating marker to select the proper OJ to match the application desired. This testing method is made possible by the fact that the coin OJ is designed to provide all the features of a regular OJ along with its expanded coin OJ requirements and as such should be tested as a regular OJ. Briefly, in operation, at the successful completion of the ATS test of OJ, OH, a check is made to determine if the OJ has ticketing contacts. If so, the contact status is examined via the ticketing scanner if the OJ is a metering or regular type. If the OJ type is coin, preparations are made to test the coin OJ as a Regular OJ. First the information identifying the OJ and ticketing contacts are copied out of the work area to a temporary storage area. The selector inlet information is then copied out of the AST routining table to temporary storage. The work area and ATS routining table are then cleared (set to zero). The pertinent information is then returned to the work area and routining table from the temporary. The ATS Main Test Mode and Sub-test Mode is then set to the values used for Regular OJ testing in the routining table. Finally an ATS software utility module is scheduled to clear the ATS hardware. In the process of clearing the ATS hardware the network paths required to test the coin OJ are dropped and the coin OJ is ready to test again. The return point specified to the utility module is the beginning of the OJ routining module, where the coin OJ is tested again as a regular OJ. This time the ticketing contacts are thoroughly tested. At the completion of the coin OJ test as a regular OJ, control is returned to the ATS control package which has been oblivious to the additional test.

Several system subroutines are called by V57-OJTEST, of which those pertinent to this disclosure are now provided.

1. Register sender access F08X02 — is used to read and read/modify/write into the register sender core memory.
2. Ticketing scanner unit input/output handler F72X01 — reads the status of the ticketing slave relays.
3. Ticketing seizure module T01X04 — insures that the ticketing contact is not being scanned by the hardware scanner.
4. Maintenance and control center input/output handler V01X05 — is used to read and write into the MRA register of the MRL.

5. Originating path setup V95X01 — is used to establish an originating path through the line matrix and OJ.
6. Terminating path setup V96X02 — is used to establish a terminating path through the selector matrix to an STO.
7. Maintenance routine logic sequence V27X02 and V27X04 — is used to either start or end the MRL sequence of operation, respectively.

System Operation

Considering now a detailed system operation, module V57 first performs a series of tests on the coin OJ in block 300 of FIG. 2 that are not pertinent to this disclosure, but some will be discussed to orient the testing sequence that is to follow. V57 schedules ORIGSU-V95X01 to pull an originating path to the desired coin OJ. The mark area was properly formatted for ORIGSU by the automatic test system control software module SPEARS prior to scheduling OJ TEST at V57X01. The return identity specified to ORIGSU is V57X02, which when entered determines if ORIGSU was successful. If successful, OJ TEST supplies the STO identity to be used in the test to MRLSEQ at V27X02 to perform an MRL start sequence. The main test made MTM and sub-test made STM information for the MRL were previously formatted by SPEARS. The MRLSEQ is scheduled and V57X03 is identified as the return to OJTEST after a successful start sequence. At this point, the work area is formatted to pull a path from the STI to the line picked by ORIGSU, which is accomplished by using TERMSU-V96X01 with the return identity specified as V57X04. When V57X04 is scheduled and after determining that TERMSU was successful, word A of the MRAI register in the MRL circuit is read to check the sequence state of the MRL. The MRL should be in sequence state four if the MRL interfaced properly with the terminating pull path through the selector matrix. If the MRL has advanced properly, the TERMSU portion of the work area is zeroed out. The TGN value of the STO is then retrieved from table HLI and is used to access the appropriate COX table to retrieve the switching digits of the STO, which are then stored in the work area for TERMSU. The selector matrix inlet identity of the coin OJ is then transferred from table RLW to the work area for TERMSU. An initial IN value of four is specified for the RJ with an IN = 10 to be written upon a successful path pull. Just prior to scheduling TERMSU, a read-modify/write of the RJ slot is performed. The cut-through type specified by the SPEARS module in table RLW is written into the RJ slot and the freeze bit is reset. TERMSU is then scheduled with a return identity of V57X05 specified. The terminating marker has been instructed to set up a path from the selector matrix inlet associated with the coin OJ to the selector matrix outlet STO 46 circuit. The register sender unit 20 has also been instructed to cut the coin OJ through to the selector matrix inlet. The common logic unit 22 also places a ground potential on the C3 lead 212 to operate relay coil K6 in the coin OJ when cut through occurs. The coin OJ relay logic required to perform the cut through operation is not pertinent to this disclosure and has not been shown in FIG. 1. The MRL 51, having received its directions from the central processor, has enabled the interface unit 52 MGS gate 54 from lead 215 to switch a ground to operate relay coil K4 in the coin OJ. After

- V57X05 is scheduled by TERMSU and the terminating marker response indicates a successful network operation, the automatic test system MRAI register is read and checked for the proper sequence state, SSX X 7, 5 for the MRL to have advanced to for enabling MRS gate 54. V57 then interrogates a flag to determine if the RJ RFT interrupt has occurred, in which case control is directly transferred to V57X06. If the RFT interrupt has not occurred, V57X06 is put on a timer queue for 10 50 milliseconds before checking for the RFT interrupt again. When V57X06 is scheduled from the timer queue and checking that the RTF interrupt has occurred, word 2A of the RJ slot is read using F08X02. The TRI field is examined for a successful cut through 15 indication from the register sender. The register sender unit is instructed to perform a read/modify/write of the RJ slot to clear down the RJ. After a 700 millisecond time interval has elapsed, which allows for the RJ to clear down, V57X07 is entered and the MRAI is again 20 read to check for the expected results, in block 301, all tests have passed the ticketing contact availability is checked in block 302. If a ticketing contact is indicated to exist, the ticketing scanner unit 30 is instructed in block 303 to get the ticketing scan points from the TIN table and transfer to the ticketing scanner handler module F72X01 to retrieve the status of slave relay contact K10-A and return the results through the scanner peripheral adapter 33 to the central processor for OJTEST to check in block 304. If the OJ type is a coin OJ without ticketing contacts or a regular OJ, then OJTEST in block 314 sets the appropriate pass or fail 25 indication in block 311 removes the MRL interrupt routine, and schedules the SPEARS control module, block 313, at V31X04.
- If the OJ type is coin, checked in block 304, with ticketing contacts, the work area and table RLW are initialized to reflect a regular OJ type of test to be performed. This is accomplished by transferring the OJ identity and ticketing contact identity from the work 30 area to a temporary storage location in block 306 and also transferring the selector matrix inlet SXI identity of the coin OJ from the routining RLW table to a temporary storage location in block 307. Both the work area and the routining table area initialized to zero in 35 block 308 in preparation for testing the coin OJ as a regular OJ. The OJ identity and the SXI identity are then restored to their respective work area and RLW routining table locations in block 309. V27X04 is then scheduled to execute an MRL end sequence in block 310 with OJTEST V57X01 specified as the return point to now test the coin OJ as a regular OJ. When V57X01 is scheduled the originating path is again established via ORIGSU to the coin OJ as previously disclosed. When ORIGSU is successful and V57X03 is entered, the work area is formatted for TERMSU to pull 40 a path from the coin OJ to the STO circuit. But before TERMSU is given control, the status of the ticketing scanner unit slave relay contact K10-A is read to insure that the relay contact is open before the terminating path is pulled. The TDB 31 interrupts the central processor and the SPA register data is read and passed to OJTEST for analysis. If the relay contact K10-A has indicated itself in an open condition, OJTEST then instructs the terminating marker to pull the selector matrix path to the STO 46 circuit. The coin OJ relay coil K6 is not operated or checked during this test. The 45 MRL is now instructed to operate MGS gate 54 to

switch a ground potential on ST lead 47. In this sequence relay coil K4 operates and closes the normally-opened contact K4-C, which provides a path for the ST lead ground potential to remain on relay coil K4 through normally-closed contact K6-B for the normally-closed contact K4-B now opens and removes this first path of ground potential to relay coil K4. The normally-opened contact K4-A also closes to energize relay coil K10, which closes its normally-opened contact K10-A. This sequence is verified by requesting the ticketing scanner unit to monitor this operation of

the slave relay K10 and forward this status to the central processor to be passed to OJTEST. If this test is successful, checked in block 301, the OJ type is checked in block 302 and found to be a regular OJ type of test. This results in an all tests pass indication being set in block 312 and scheduling a return to the calling program, which is SPEARS at entry point V31X04.

As a part thereof, Appendix A contains the actual module listings, which contain all the processor instructions necessary to perform the appropriate software operations of the communication switching system.

What is claimed is:

- In a communication switching system having a switching network for establishing connections between calling and called lines in response to common equipment and having a plurality of space-divided equipment units communicating with the common equipment for performing control operations, the common equipment including scanning means for monitoring the space-divided equipment units, each one of the space-divided equipment units including a supervisory device for generating a supervisory signal and for sup-

plying it to said scanning means, a method of in-circ testing of space-divided equipment devices, comprising:

providing testing means for controlling one of space-divided equipment devices under test; establishing a test connection through the network between said testing means and the device under test; causing said testing means to control the operation of the device under test and thus to control the generation of its supervisory signal for testing purposes.

causing said scanning means to sense the supervisory signal of the device under test; and determining whether the device under test is able to operate properly in response to said scanning means.

2. A method according to claim 1, wherein said supervisory signal is ticketing information.

3. A method according to claim 2, wherein said space-divided equipment units comprise junctors.

4. In a communication switching system having a switching network for establishing connections between calling and called lines in response to common equipment and having a plurality of space-divided equipment units communicating with the common equipment for performing control operations, the common equipment including scanning means for monitoring the space-divided equipment units, each one of the space-divided equipment units including a supervisory device for generating a supervisory signal and for supplying it to said scanning means, an apparatus for in-circuit testing of the space-divided equipment devices, comprising:

5 testing means for controlling one of the space-divided equipment devices under test; means for establishing a test connection through the network between said testing means and the device under test; means for causing said testing means to control the operation of the device under test and thus to control the generation of its supervisory signal for testing purposes; means for causing said scanning means to sense the supervisory signal of the device under test; and means for determining whether the device under test is able to operate properly in response to said scanning means.

15 5. An apparatus according to claim 4, wherein said supervisory signal is ticketing information.

6. An apparatus according to claim 5, wherein said space-divided equipment units comprise junctors.
